UNITED STATES PATENT OFFICE.

EARL C. POWELL, OF CHESTER, WEST VIRGINIA.

DESIGN FOR A CROCHET-BALL HOLDER.

52,104.

Specification for Design. Patented June 11, 1918.

Application filed March 13, 1918. Serial No. 222,245. Term of patent 7 years.

To all whom it may concern:

Be it known that I, EARL C. POWELL, a citizen of the United States, and a resident of Chester, in the county of Hancock and State of West Virginia, have invented a new, original, and ornamental Design for a Crochet-Ball Holder, of which the following is a specification, reference being had to the accompanying drawing, form part thereof.

The figure is a perspective view of a crochet ball holder, embodying my design.

I claim:

The ornamental design for a crochet ball holder, as shown.

EARL C. POWELL.

Witnesses:

W. C. BEALL,
H. G. MERCER.
